UNITED STATES PATENT OFFICE.

IVER H. LEE, OF VIBORG, SOUTH DAKOTA.

HAY-RACK CLAMP.

1,143,495.

Specification of Letters Patent.

Patented July 6, 1915.

Application filed November 2, 1914. Serial No. 869,858.

To all whom it may concern:

Be it known that I, IVER H. LEE, a citizen of the United States, residing at Viborg, in the county of Turner, State of South Dakota, have invented certain new and useful Improvements in Hay-Rack Clamps; and I do hereby declare the following to be a full, clear, and exact description of the invention, such as will enable others skilled in the art 10 to which it appertains to make and use the same.

This invention relates to clamps, particularly to clamps for securing a hay rack, and has for its object the provision of a clamp 15 whereby a hay rack may be secured without the necessity for boring holes in the rack, thereby weakening the same.

An important object is the provision of a clamp which will be quickly and easily attached and detached, which will be secure and fast in its action, durable in service and a general improvement of the art.

With these and other objects and advantages in view the invention consists in the 25 novel construction and arrangement of parts as will be hereinafter more fully described and claimed and illustrated in the accompanying drawing, in which—

Figure 1 is a perspective view of my novel 30 clamp applied to a hay rack and in its unlocked position. Fig. 2 is a view looking at a cross bar of the rack showing my clamp in its locked position. Fig. 3 is a similar view looking at the face of the side bar, and 35 Fig. 4 is a detail horizontal sectional view.

Referring more particularly to the drawing the numeral 5 designates a bed piece of my rack and 6 designates a cross bar on the bed piece 5.

40 In order that the cross bar 6 may be clamped upon the bed piece 5 I provide an upright member 8 formed as a rod having an offset portion 9 adjacent its lower end and terminating in a hook 10 engageable beneath the bed piece 5. The upper end of the rod 8 is screwthreaded as shown at 11 for the reception of a nut 12. A second rod 13 is adapted to coact with the rod 8 and comprises a straight portion 14 bent intermediate its ends to form a loop 15, terminating at its lower end in a loop 16, the loops 15 and 16 being disposed upon the upright member 8. The rod 13 terminates at its upper end in a loop 17 which is engaged by 55 a movable clamping member to be described.

The movable clamping member comprises

a straight bar 18 provided at one end with a loop 19 engaging the loop 17, bent at right angles as shown at 20 and adjacent the loop 19 and terminating at its other end in a reflexly bent loop 21. A ring 22 is disposed slidably upon the rod 13 for a purpose to be described.

My device is used as follows: The rod 13 is positioned against the side of the cross bar 6, with the hook 10 engaging the lower side of the bed piece 5. The rod 13 is then disposed in relation to the rod 8 with the loops 15 and 16 engaging upon the rod 8, from which they will be prevented from removal by the nut 12. The locking rod 18 is then swung over the cross bar 6 and swung downwardly until the hook 21 is adjacent the rod 13. The ring 22 is then slid over the hook 21 to hold the rod 18 against outward and upward movement, thereby clamping the cross bar 6 firmly and securely upon the bed piece 5. In order to release the clamp it is merely necessary to move the ring 22 upwardly until it disengages the hook 21 whereby the rod 18 can be moved upwardly out of engagement with the cross bar 6. If it should be desired to adjust the rod 13 relatively to the bed pieces 5 in order to clamp larger or smaller cross bars, such may be readily accomplished by rotating the nut 12 in the proper direction to raise or lower said rod on the upright member 8. It is to be noted that when applied the nut 12 has one of its flat faces bearing against the bed piece 5, the nut being in this manner held against rotation and accidental displacement of the parts prevented.

From the foregoing description and a study of the drawing, it will be apparent that I have thus provided a novel and simple hay rack clamp which will be easy to attach, and detach, positive and secure in its action, and not likely to get out of order.

It will be readily understood that I reserve the right to make various changes in the form, construction and arrangement of parts without departing from the spirit of the invention or limiting the scope of the subjoined claims.

Having thus described my invention, I claim—

1. A clamp for hay racks comprising a rod hooked at one end to engage beneath a side bar, a second rod slidably adjustable upon said first named rod, a ring slidable on said second named rod, and a clamping

rod pivoted upon the outer end of said second named rod, extending above and around a cross bar and a reflexly bent hook upon the other end of said second named rod, said second named hook being engageable by said ring for preventing outward movement of said last named rod.

2. A clamp for hay racks comprising a rod hooked at one end for engagement beneath a side bar, and provided upon its other end with a screwthreaded portion, a second rod bent intermediate its ends and at its lower end to form loops disposed upon said first named rod, a nut threaded on the outer end of said first named rod and having one

side engaging said side bar, said nut bearing against the top of said intermediate loop, a loop formed on the upper end of said second named rod, a ring slideable upon said second named rod, and an angular clamping rod provided upon one end with a loop engaging said last named loop and provided upon its other end with a reflex bent hook engageable by said ring.

In testimony whereof, I affix my signature, in the presence of two witnesses.

IVER H. LEE.
